UNITED STATES PATENT OFFICE.

LOUISE TULLY, OF NEW YORK, N. Y., ASSIGNOR TO THE BUTTERICK PUBLISHING COMPANY, (LIMITED,) OF SAME PLACE.

DESIGN FOR A LADY'S COAT.

SPECIFICATION forming part of Design No. 14,833, dated February 26, 1884.

Application filed January 23, 1884. Term of patent 3½ years.

To all whom it may concern:

Be it known that I, LOUISE TULLY, of the city, county, and State of New York, have invented and produced a new and original Design for a Pattern of a Lady's Coat, (numbered 9,017;) and I do hereby declare that the engraved prints accompanying this specification convey to any one accustomed to using paper patterns a clear understanding of how a garment made up by the pattern will appear.

The design shows a vest extending the full length of the garment, with its upper portion drooping in a deep puff over the plaited lower portion; closely-fitted side fronts; a

closely-fitted back, displaying a lap at the lower end of its center seam, and coat-plaits at the side-back seams; a deep shoulder-cape gathered to stand high at the shoulders; a rolling collar, and coat-sleeves.

What I claim as my invention, and desire to secure by Letters Patent, is—

The design for a lady's coat, as shown in the engraved prints accompanying this specification.

LOUISE TULLY.
